UNITED STATES PATENT OFFICE

151,701

DESIGN FOR A TABLE OR SIMILAR ARTICLE

Eugene J. Lux, New York, N. Y., assignor to
Columbia Protektosite Company, Inc., Carl-
stadt, N. J., a corporation of New Jersey

Application March 28, 1947, Serial No. 138,020

Term of patent 7 years

(Cl. D33—14)

To all whom it may concern:

Be it known that I, Eugene J. Lux, a citizen of the United States, and resident of New York city, in the county of New York and State of New York, have invented a new, original, and ornamental Design for a Table or Similar Article, of which the following is a specification, reference being had to the accompanying drawing, forming a part thereof, and of which Fig. 1 is a view in side elevation of a table or similar article showing my new design; Fig. 2 is a bottom plan view thereof; Fig. 3 is a horizontal sectional view on the line 3—3 of Fig. 1; Fig. 4 is a fragmentary vertical sectional view taken on the line 4—4 of Fig. 1.

The four legs of the table are identical in design, and the top of the table is plain.

I claim:

The ornamental design for a table or similar article, substantially as shown and described.

EUGENE J. LUX.
